Patented Feb. 22, 1966

203,811

PORTABLE FOOT SWITCH RETAINING PAD FOR SEWING MACHINES

Hazel Ruedin, 1825 N. Wilcox Ave., Los Angeles, Calif.

Filed July 7, 1965, Ser. No. 86,056

Term of patent 14 years

(Cl. D9—6)

Fig. 1

Fig. 2

Fig. 3

Fig. 4

Fig. 5

FIG. 1 is a top plan view of a portable foot switch retaining pad for sewing machines, showing my new design;

FIG. 2 is a sectional view taken on line 2—2 of FIG. 1;

FIG. 3 is a front elevation view thereof;

FIG. 4 is a rear elevation view, and

FIG. 5 is a bottom plan view of the same.

I claim:

The ornamental design for a portable foot switch retaining pad for sewing machines, substantially as shown.
